UNITED STATES PATENT OFFICE.

WILLIAM P. GROSS, OF SEBEWAING, MICHIGAN.

SEPARATING DEVICE.

1,242,683.

Specification of Letters Patent.

Patented Oct. 9, 1917.

Application filed March 17, 1917. Serial No. 155,529.

To all whom it may concern:

Be it known that I, WILLIAM P. GROSS, a citizen of the United States, residing at Sebewaing, in the county of Huron and 5 State of Michigan, have invented certain new and useful Improvements in Separating Devices, of which the following is a specification, reference being had to the accompanying drawings.

10 This invention relates to certain improvements in separating devices and it is an object of the invention to provide a device of this general character especially designed and adapted for use in connection with a 15 bean picker and having novel and improved means whereby the beans or the like may be manually separated with convenience and facility.

It is also an object of the invention to 20 provide a novel and improved device of this general character including a hopper and an assorting table or chute engaged with the hopper and upon which said hopper discharges together with means whereby said 25 table or chute may be readily adjusted longitudinally into different inclinations or pitches as the requirements of practice may necessitate.

The invention consists in the details of 30 construction and in the combination and arrangement of the several parts of my improved separating device whereby certain important advantages are attained and the device is rendered simpler, less expensive and 35 otherwise more convenient and advantageous for use, all as will be hereinafter more fully set forth.

The novel features of the invention will 40 hereinafter be definitely claimed.

45 In order that my invention may be the better understood, I will now proceed to describe the same with reference to the accompanying drawings, wherein—

Figure 1 is a longitudinal sectional view 45 taken through a separating device constructed in accordance with an embodiment of my invention.

Fig. 2 is a bottom plan view of the device as herein disclosed;

50 Fig. 3 is a sectional view taken substan-

tially on the line 3—3 of Fig. 1 with one of the vertical rods broken away; and

Fig. 4 is a view in elevation of the valve as herein employed.

As disclosed in the accompanying drawings, H denotes a hopper of any desired configuration and dimensions and which is provided in its bottom and at an end thereof with the open-ended slot 1 extending within the hopper and affording a discharge opening. The opening as afforded by the slot 1 is substantially defined by a plate 2 partially overlying said opening and coacting with the bottom of the hopper to afford a guideway 3 to receive the marginal portions 65 of the slide valve 4 whereby the discharge through said opening in the bottom of the hopper H may be readily and conveniently controlled.

The under surface of the bottom of the 70 hopper H is provided with the elongated resilient rods 5 arranged in parallelism and positioned at opposite sides of the slot 1 with the end portions of said rods 5 remote from said slot suitably anchored, as indicated at 6, to the bottom of the hopper.

C denotes an elongated chute or table of 75 predetermined dimensions and provided at one end with the substantially U-shaped flange 7, the side members of which extending longitudinally of the chute or table. The flange 7 is adapted to extend within the slot 1 and serves to prevent a scattering of the beans or the like discharged through the slot 1 upon the chute or table C and which 85 would also have a tendency to interfere with the vibration of the chute or table.

The chute or table C in advance of the flange 7 and adjacent the opposite longitudinal margins of the chute or table are 90 outwardly offset, as indicated at 8, and said offset portions are provided with the perforations or openings 9 through which the free end portions of the rods 5 are adapted to be directed and whereby said rods 5 serve 95 to maintain the chute or table C in applied position relative to the hopper H and also permits said chute or table to have vibratory movement.

The end portion of the chute or table C 100

intermediate the openings 9 is provided with a third opening 10 adapted to receive the angular end portion of the elongated latch member 11 pivotally engaged with the under surface of the bottom of the hopper H at a predetermined point inwardly of the slot 1. As is believed to be clearly apparent to those skilled in the art to which my present invention appertains, the latch member 11 serves to effectually hold the chute or table C against outward longitudinal movement which would result in the displacement of said table or chute.

In practice the chute or table C is disposed longitudinally on a predetermined incline or pitch which is insufficient to permit the beans or the like to roll by gravity therealong but which will permit said beans to travel downwardly of the chute as said chute is caused to vibrate by the picking action of the operators who are arranged along opposite sides of the chute. As the beans or the like are delivered upon the chute or table C the operators push or pick the bad beans off of the chute or table with the thumb and forefinger of each hand and which operation results in a vertical vibration of the chute or table C.

In order that the inclination or pitch of the chute or table C may be readily regulated in accordance with the necessities of practice and especially when the bottom of the chute C is substantially level, I dispose across the outer face of the end of the hopper adjacent the slot 1 the plate 12 provided at opposite sides of the slot 1 with the vertically disposed guideways 14. Extending through the guideways 14 are the elongated rods 15, the lower ends of which are being adapted to engage with the upper surface of the chute or table C at a point adjacent the hopper H while the upper end portions of said rods are angularly disposed, as indicated at 16, and adapted to be seated within the vertically disposed series of recesses 17 produced in the outer face of the adjacent end portion of the hopper. By this arrangement it will be perceived that when the angular portions 16 of the rods 15 are seated within the recesses 17, the rods 15 are held against upward movement by the pressure imposed thereupon by the chute or table C and which results in said chute or table C being maintained on a predetermined incline or pitch.

From the foregoing description, it is thought to be obvious that a separating device constructed in accordance with my invention is of an extremely simple and comparatively inexpensive nature and is particularly well adapted for use by reason of the convenience and facility with which it may be assembled, and it will also be obvious that my invention is susceptible of

some change and modification without material departure from the principles and spirit thereof and for this reason I do not wish to be understood as limiting myself to the precise arrangement and formation of the several parts herein shown in carrying out my invention in practice, except as hereinafter claimed.

While the valve 4 has hereinbefore been described as movable within the guideway 3, the same is also adapted to be positioned vertically as illustrated in Figs. 1 and 3, and when so arranged said valve 4 is inserted between the plate 12 and the adjacent end of the hopper H. The lower end of the valve has a substantially crescent portion cut out, as indicated at 18, for the passage of the beans outwardly of the chute C under normal conditions. It will be understood however that the valve 4 may be raised or lowered to control the passage or flow of the beans or the like to be picked as the requirements of practice may necessitate. In order to facilitate the operation of the valve the upper end portion thereof is provided with the outwardly disposed flange 19.

I claim:

1. In combination with a hopper provided with a discharge opening, an elongated table having one end portion underlying the discharge opening of the hopper, a flange carried by the table and extending within the discharge opening of the hopper, said flange partially conforming to the contour of said opening, and resilient means carried by the hopper for supporting the table in applied position. 95
2. In combination with a hopper provided with a discharge opening, a resilient rod anchored at one end to the hopper, and an elongated table having one end portion underlying the discharge opening of the hopper, the underlying end portion of said table being engaged with the free end portion of the rod. 105
3. In combination with a hopper provided with a discharge opening, a resilient rod carried by the hopper, an elongated table having one end portion underlying the discharge opening of the hopper, said table being detachably engaged with the rod, and means carried by the hopper and engageable with the inner end of the table for holding the table against movement longitudinally of the rod. 115
4. In combination with a hopper provided with a discharge opening, a resilient rod carried by the hopper, an elongated table having one end portion underlying the discharge opening of the hopper, said table being detachably engaged with the rod, and a latch carried by the hopper and detachably engaged with the inner end of the table for 125

holding the table against movement in one direction longitudinally of the rod.

5. In combination with a hopper provided with a discharge opening, an elongated table having one end portion underlying the discharge opening of the hopper, resilient means carried by the hopper for supporting the table in applied position, and an upstanding flange carried by the table and

extending within the discharge opening of 10 the hopper, said flange being substantially U-shaped in form.

In testimony whereof I hereunto affix my signature in the presence of two witnesses.

WILLIAM P. GROSS.
